CLAIM

The ornamental design for a combined stove door supported thermostat and damper shielding housing with access shielding lower barrier, as shown and described.

DESCRIPTION

FIG. 1 is a front perspective view of a combined stove door supported thermostat and damper shielding housing with access shielding lower barrier embodying my new design, viewed from above and to the front of the housing;

FIG. 2 is a rear perspective view thereof, viewed from below and to the rear of the housing; and
FIG. 3 is a rear elevation view thereof.
